UNITED STATES PATENT OFFICE.

JOHN R. GREEN, OF GIRARD, TEXAS.

ADJUSTABLE LUGGAGE-CARRIER.

1,373,502.

Specification of Letters Patent. Patented Apr. 5, 1921.

Application filed November 5, 1917. Serial No. 200,270.

To all whom it may concern:

Be it known that I, JOHN R. GREEN, a citizen of the United States, residing at Girard, in the county of Kent and State of Texas, have invented certain new and useful Improvements in Adjustable Luggage-Carriers, of which the following is a specification.

My invention has relation to luggage carriers for vehicles and in such connection it relates more particularly to an adjustable carrier to be used on the running board of an automobile to carry parcels, small packages or bulky merchandise.

Heretofore articles carried on the running board of automobiles have been strapped, wired or tied with strings and this necessitated tying, untying, etc., and consumed time and trouble in securely fastening such articles to the running board, not to mention the probability of their being lost en route.

The principal object of my invention is to provide a luggage carrier which is adjustable, of cheap manufacture, durable, and one which will be out of the way of the passengers.

In the carrying out of my invention I provide a frame of strong metal or iron of a size to fit the width and approximate length of the running board when the carrier is extended its full length and width. Inside of this frame is placed a small wire basket of small mesh, to carry small articles, this basket being in two sections, so that when the frame is extended it can be taken out if desired, and when the frame is reduced to its smallest compass the two sections of the basket fit together making a receptacle for a number of small articles or packages.

The nature and scope of my invention will be more fully understood from the following description, taken in connection with the accompanying drawings, forming part hereof, in which—

Figure 1 is a side elevational view of my improved luggage carrier.

Fig. 2 is a top plan view of the same.

Fig. 3 is an end view of the carrier.

Fig. 4 is a cross-sectional view, taken on the line 4—4 of Fig. 1.

Fig. 5 is a perspective view of the wire basket.

Fig. 6 is a cross-sectional view showing the means for locking the sliding bars, and

Fig. 7 is a cross-sectional view taken on

the line 7—7 of Fig. 3 and illustrating the mode of clamping the frame to the running board of an automobile.

Referring more particularly to the drawings, 1 and 2 represent the side bars of the frame of my adjustable luggage carrier, the edges of bar 1 being turned or curved inwardly to form a groove in which bar 2 slides. These bars, 1 and 2, are riveted to corner posts 3 and 4 and are then bent around these posts to form end bars 4^a and 5 of the frame, and the same process—that of bending or curving the edges of one of the bars inwardly to form a groove in which the other bar slides—is repeated at the end construction of the frame. The carrier can then be either lengthened or widened and when the proper size is obtained the frame is locked in place by a series of flat springs 6 placed on both grooved bars at the ends of the frame as shown in Fig. 3, a detailed view of which is shown in Fig. 6. On the under surface of these springs is a pin 6^a which, when inserted through one of the holes 7 in the other end bar, securely holds the frame in its adjusted position.

The two front corner posts 3 of the frame extend down to the running board 7^a, while the rear posts 4 next the body of the automobile extend only half way down, being held together there by the middle bars of the frame. This leaves a space between the two front posts and the side of the body of the automobile in which material like bedding, etc., may be placed and which would be held in place by the front posts of the frame.

The frame of the luggage carrier is held in place on the running board by angle irons 8, one at each end of the frame, the angle iron being curved or bent over the edge of the bottom bar at the ends of the frame, as shown in Figs. 1 and 7. A butterfly screw 9 one on each angle iron holds the iron in place on the running board and securely holds the frame thereon.

The wire basket or cage shown in Fig. 5 is made of small mesh wire and is constructed in two halves or sections as illustrated at 10 and 11, Fig. 5, the object being to provide a receptacle for small articles when the frame is reduced to its smallest compass, the two inner ends of the halves or sections abutting one another.

Having thus described the nature and ob-

jects of my invention what I claim as new and desire to secure by Letters Patent, is—

The combination in an adjustable luggage carrier for automobiles of four upright members forming a rectangular space, two pairs of horizontal members connected to the upright members at each end to form ends of the carrier, two pairs of horizontal members connected to said upright members to form the side next the automobile, and three pairs of horizontal members in front,

the upright members next the automobile being shorter than those in front, all said horizontal members slidably arranged one on the other and adapted to increase or decrease the width and length of said carrier, and a spring means for locking said horizontal members in position.

In testimony whereof I have signed my name to this specification.

JOHN R. GREEN.
